RELAY

William D. Hailes and Walter H. Hoppe, Rochester, N. Y., assignors to General Railway Signal Company, Rochester, N. Y.

Application January 14, 1931. Serial No. 508,659

15 Claims. (Cl. 200—93)

This invention relates to electrical relays and more particularly to the type of electrical relays used in railway centralized traffic control systems.

In certain centralized traffic control systems it has been found advantageous to employ relays which are operable to two distinct positions in accordance with the energizing polarity, and which remain in either of such positions after interrupting the operating current. A relay, used 10 in such a system, is necessarily of small dimensions and simple construction, as a large number is employed and usually grouped in a comparatively small space.

With these and other considerations in mind, 15 it is proposed in accordance with this invention to provide a small and easily constructed electromagnetic relay with an attracted and a retracted armature position, and including a permanent magnet whereby the armature, after being positioned by a definite polarity of operating energy, is held in such an attracted position until it is released by the application of a current of opposite polarity.

Other objects, purposes, and characteristic features of the invention will appear as the description thereof progresses, reference being made to the accompanying drawing which shows, solely by the way of example, and in no manner in a limiting sense, one form which the invention can 25 assume, and in which:—

Fig. 1 is a top plan view of a relay according to this invention with a part shown in section to illustrate the electro-magnet construction.

Fig. 2 is a side elevation of the relay of Fig. 1. 35 Fig. 3 is an end elevation of the same relay. Fig. 4 is a sectional view on line 4—4 of Fig. 1 and Fig. 2, as viewed in the direction of the arrows.

Referring now to the accompanying drawing, 40 the relay comprises an elongated core 1 with a smaller diameter threaded mounting extension 1¹, which holds a non-magnetic supporting member 2 and a magnetic member 3 by a nut 4 clamping them against a shoulder made by the larger 45 diameter of core 1. A spool 5 is carried by core 1 and held in place thereon by a spring washer 6 urging it against a retaining ring 7 which is a spring fit into an annular slot in the free end of core 1.

50 Spool 5 contains a winding 8 concentrated at the rear end thereof and a wood spacing washer 9 filling the remaining space. The wood spacing washer has an enlarged end 9¹ with the smaller circular portion and the winding 8 taped overall 55 in assembly.

The magnetic member 3 has two inwardly extending strip portions 3¹ and 3² which extend parallel to and equally spaced from the spool 5 with their free ends sprung to rest firmly against the sides of the spool 5. Also included on the 60 magnetic member 3 is an L-shaped supporting portion 3³, which holds a permanent magnet 13 adjustably clamped thereto by screws 14 and holding a clamp 15, so as to extend beneath and parallel to the spool 5 with its free end resting 65 firmly against the lower side of the enlarged end 9¹ of the wood spacing washer 9. The ends of the spool 5 have flat top surfaces to engage the lower side of the non-magnetic supporting member 2 which member extends along the top of the spool 70 5 and thus prevents turning of the spool 5 on the core 1.

Over an acute angled edge at the free end of the supporting member 2 is pivoted an armature 16, constructed of suitable low residual magnetic 75 material and formed to an obtuse angle to have a distinct inside corner edge resting on the aforesaid acute angle of the supporting member 2. The top portion of the armature 16 has a central oblong slot 17 extending through the bend therein, 80 and a bridge member 18 is riveted to the top end and is bent downwardly to engage the supporting member 2 to serve as a stop for limiting the armature's motion in the non-attracted direction.

The lower part of armature 16 extends downwardly in front of the free end of core 1 and the free end of the permanent magnet 13. A residual screw 19 of non-magnetic material is threaded into the extreme lower end of armature 16 and locked in an adjusted position by nut 20, thus 90 adjusting the movement of the armature toward the permanent magnet 13.

A T-shaped retaining member 21 is placed in the armature slot 17, so as to be free from the edges thereof and is held in a spline in the supporting member 2 by a screw 22 threaded to clamp it therein. The ends 21¹ of the retaining member 21 have edges cut at an oblique angle which rest against the outside arc of the bend in the armature 16 to thus provide a retainer which 95 offers slight resistance to the pivoting motion about the acute edge of the supporting member 2.

An offset bracket 23 is secured to the supporting member 2 by screws 24 and holds a number of contact banks which may be varied to meet the particular requirements, but is illustrated as being two banks of like construction. These banks include resilient front contact fingers 25, similar inverted fingers or back contact fingers 26 and movable contact fingers 27. Rigid stops 28 are 100 110

mounted between both front and back contact fingers and the movable contact fingers to thus limit the resilient motion in this direction. The contact fingers are each separated from each other and separated from the bracket 23 by insulating spacers 29. Each bank also includes a soldering lug 30 mounted beneath the bracket 23, and separated therefrom by an insulating spacer 29, to which are soldered winding leads 31, which are carried from the winding 8 through insulating bushings 32 held in holes in the supporting member 2.

Each bank is firmly held in its assembled position on the bracket 23 by two through bolts 33 with suitable insulating bushings on their body portions (not shown) and with their heads bearing on a metal washer 34 which is also separated from the top finger by an insulating spacer 29. These through bolts 33 are held and locked by nuts 35 which are insulated from the soldering lugs 30 in the same manner as the heads of the through bolts 33 as previously described.

The contact fingers 25, 26 and 27 are made of suitable flat spring material, such as phosphor bronze, and are allowed to extend a short distance in the rear of the insulating spacers 29 to facilitate in soldering external wire connections. The other end of each of the contact fingers 25 and 26 is bifurcated by a slot 36 with a suitable low resistance arc resisting contact point 37 near the extreme end of each fork, thus providing an individually resilient portion for each low resistance contact point.

The movable contact fingers 27 have two double faced low resistance arc resisting contact points 38 arranged to be engageable with the low resistance arc resisting contact points 37 on either the front contact fingers 25 or the back contact fingers 26. These movable fingers 27 have two holes 40 near their extreme end to receive insulating connecting rods 39 which are employed to operatively interconnect all the movable fingers 27 of each bank and the lower movable finger to the bridge 18 of the armature 16.

45 An armature biasing spring 40 is clamped between the two contact banks on the bracket 23 by bolts 41 secured by nuts 42. The spring 40 is made of flat resilient material similar to that used in the contact fingers and extends forward with a slight downward bend to allow its extreme end to press downwardly on the bridge 18 of the armature 16.

It is apparent from the foregoing description and by referring to Fig. 2 that when the winding 8 is deenergized the permanent magnet 13 causes a flux to flow through the armature 16, core 1 and the supporting portion 3³ of the magnetic member 3. This flow of flux causes a force to act on armature 16 which tends to draw the lower end into contact with the permanent magnet 13 but the biasing spring 40 is adjusted so as to exert a slightly greater counter force which results in maintaining the armature 16 out of contact with permanent magnet 13.

65 Assuming that the permanent magnet 13 is so clamped in the relay assembly that its free end is the north pole, the flux emanating therefrom flows into the armature 16 and returns through the core 1 and the magnetic member 3. 70 If a current is now caused to flow in a direction in the winding 8 so that the free end of core 1 is made a south pole, the magnetomotive force is additive in direction to the magnetomotive force of the permanent magnet 13. This cumulative magnetomotive force results in the flow of flux in

the armature of a value that the force produced is sufficient to overcome the reaction of the biasing spring 40. The armature 16 is thus moved about its pivot point, into contact with the permanent magnet 13 lifting the bridge 18 from the supporting member 2 which raises the movable contact fingers 27 into engagement with the stationary front finger 25.

If now the current flow in the winding 8 is interrupted, the armature 16 still remains against the permanent magnet 13, because its movement to this position decreased the reluctance of the permanent magnet flux path through the core 1 to an extent that sufficient flux now flows to exert a greater tractive force on the armature 16 than is exerted by the biasing spring 40.

The armature 16, having been thus attracted, remains in this attracted position until a current of opposite polarity is caused to flow in the winding 8. This current creates a north pole in the free end of core 1, thus resulting in a magnetomotive force counter-acting the magnetomotive force produced by permanent magnet 13. The bucking of the magnetomotive forces producing these two flux sources decreases the flux in the armature 16 to such an extent that the resulting tractive force is less than the force of the biasing spring 40. This results in releasing the armature 16 and the biasing spring 40 returns it to its normal position against the supporting member 2, which causes the movable contact fingers 27 to engage with the stationary back contact fingers 26.

To obviate the tendency of the flux from core 1 to overcome and reverse the direction of flux in the permanent magnet 13, when they are in opposition, and thus cause demagnetization of the permanent magnet 13, the winding 8 is concentrated at the rear of the core 1 with a return leakage path provided by the extending strip portions 3¹ and 3² of the magnetic member 3. The superfluous flux from core 1 by fringing out through the wood spacing washer 9 returns to the south pole through the magnetic strip portions 3¹ and 3² instead of flowing in a demagnetizing direction in the permanent magnet 13. It is probable that some permanent magnet flux, when opposed, will also fringe into the magnetic strip portions 3¹ and 3² and return to the opposite pole along with the flux from core 1.

The current required to release the armature from its attracted position can be regulated by adjusting the residual screw 19, although care should be taken not to have the retaining magnetomotive force so near the value of the spring biasing force that a possible jar might release the armature. An adjustment of the distance of the armature movement or the air gap between the armature 16 and the core 1, can also be made by sliding the permanent magnet 13 in its clamp 15.

From the accompanying drawing and the foregoing description it is seen that a very compact relay is provided which is distinctly responsive to the energizing current of one polarity if it has previously been positioned by current of an opposite polarity, or, in other words, it constitutes a relay which responds to current of a definite polarity and remains in this position after the interruption of this current and until it is released by an application of current of the opposite polarity.

The above rather specific description of one form of the present invention is given solely by way of example, and is not intended, in any man-

ner whatsoever, in a limiting sense. It is also to be understood that various modifications, adaptations and alterations may be applied to meet the requirements of practice, without in any manner departing from the spirit or scope of the present invention, except as limited by the appended claims.

Having thus described my invention, what we claim is:—

- 10 1. In a relay, an elongated core, a threaded end on said core, a non-magnetic L-shaped member and a magnetic U-shaped member secured to said threaded portion so as to extend in spaced parallel relation to said core, a permanent magnet 15 adjustably clamped to said magnetic U-shaped member so as to extend along said core and substantially equidistant from the legs of said magnetic U-shaped member, a winding on said core concentrated near the threaded end thereof, a spacer of non-magnetic insulating material between said winding and the free end of said core with means thereon for positioning the free end of said permanent magnet, a crank-shaped armature pivoted on the free end of said non-magnetic L-shaped member and movable toward the free ends of said core and said permanent magnet, a retaining member secured to said L-shaped supporting member and presenting oblique surfaces against the outside arc of said armature, a biasing spring acting on said armature and a plurality of fixed and movable resilient contact fingers operable in accordance with the position of said armature, said fixed contact fingers including contact points on bifurcated 30 free ends thereof engageable with contact points on said movable fingers.
2. In a relay, a soft iron core with a threaded mounting extension, a non-magnetic supporting member secured to said threaded mounting extension, a U-shaped magnetic member secured at its mid point to said mounting extension, a permanent magnet adjustably clamped to said U-shaped magnetic member so as to extend in spaced parallel relation to said core and equidistant from the legs of said U-shaped magnetic member, a spool on said core including a winding concentrated at the end adjacent said mounting extension and a wood spacer occupying the remaining space in said spool, an armature pivoting about the free end of said supporting member and attractable against a biasing spring toward the free ends of said core and said permanent magnet, a retaining member holding said armature in an operable position on said pivot and contact means operated in accordance with the position of said armature.
3. A relay including an electro-magnet, a permanent magnet arranged in spaced parallel relationship, and an armature attractable to bridge said electro-magnet and said permanent magnet, means biasing said armature out of said attracted position but incapable of returning the same when in said attracted position, a leakage flux path 60 extending parallel to said electro-magnet and spaced from said armature and means on said armature for adjusting the retaining force in said attracted position.
4. A relay including an electro-magnet and a permanent magnet connected at one end, a pivoted armature arranged to swing into a position magnetically bridging together the free ends of said electro-magnet and said permanent magnet, means biasing said armature out of said magnetically bridging position and means on said 70 armature for adjusting the force holding same in

said magnetically bridging position, said electro-magnet including a coil concentrated at the end connected to said permanent magnet and magnetic leakage strips paralleling said electro-magnet.

80

5. In a relay, in combination, an electro-magnet, a permanent magnet having one end magnetically connected to one end of said electro-magnet, an armature, and means for biasing said armature to a definite position, said electro-magnet being arranged to attract said armature from said biased position to a position magnetically bridging the free end of said electro-magnet and the free end of said permanent magnet, if energized by a current of one polarity, said permanent magnet being arranged to retain said armature in said attracted position upon the de-energization of said electromagnet said biasing means returning said armature when released by the application of a current of opposite polarity 95

85

6. In a polarized relay, in combination, an elongated electro-magnet, an elongated permanent magnet having one end magnetically connected to one end of said electro-magnet, a magnetic member secured at the junction of said electro-magnet and said permanent magnet having strip portions partially encircling said electro-magnet substantially spaced at right angles from said permanent magnet, a tractive armature operable 100 to complete a magnetic circuit including said electro-magnet and said permanent magnet, and biasing means effective to position said armature within a predetermined marginal value of magnetic flux therein, said electro-magnet having a 105 winding concentrated at its fixed end and a core extending beyond said winding in spaced relation to the strip portions of said magnetic member.

100

7. In a relay, in combination, an electro-magnet, a permanent magnet, an armature, means biasing said armature to a definite position, said electro-magnet being arranged to attract said armature from said biased position if energized by a current of one polarity, said permanent 115 magnet being arranged to retain said armature in said attracted position upon the de-energization of said electromagnet, said biasing means returning said armature when released by the application of a current of opposite polarity to 120 the electro-magnet.

115

8. A relay including an electro-magnet, a permanent magnet arranged in spaced parallel relationship, and an armature attractable to bridge said electro-magnet and said permanent magnet, means biasing said armature out of said attracted position but incapable of returning the same when in said attracted position, a leakage flux path 130 extending parallel to said electro-magnet and spaced from said armature.

120

9. A relay including an electro-magnet, a permanent magnet arranged in spaced parallel relationship, and an armature attractable to bridge said electro-magnet and said permanent magnet, 140 means biasing said armature out of said attracted position but incapable of returning the same when in said attracted position.

125

10. In a polarized relay, in combination, a permanent magnet, an electro-magnet, a pivoted 145 armature, elastic means biasing the armature away from said magnets, and effective to retain the armature away from the permanent magnet, when the electro-magnet is de-energized, the armature being drawn against the permanent 150

130

magnet when the electro-magnet is energized with one polarity.

11. In a polarized relay, in combination, a permanent magnet, an electro-magnet, a pivoted armature, elastic means biasing the armature away from said magnets, and effective to retain the armature away from the permanent magnet, when the electro-magnet is de-energized, the armature being drawn against the permanent magnet when the electro-magnet is energized with one polarity, the permanent magnet being effective, when the armature is against it, to prevent the elastic means from moving it away, even though the electro-magnet be de-energized.
12. In a polarized relay, in combination, a permanent magnet, an electro-magnet, a pivoted armature, elastic means biasing the armature away from said magnets, and effective to retain the armature away from the permanent magnet, when the electro-magnet is de-energized, the armature being drawn against the permanent magnet when the electro-magnet is energized with one polarity, the permanent magnet being effective, when the armature is against it, to prevent the elastic means from moving it away, even though the electro-magnet be de-energized.
13. A relay including an electro-magnet, a permanent magnet arranged in spaced parallel rela-

tionship, and an armature, positioned to one side of, and normally out of contact with, both said magnets, and attractable to bridge said electro-magnet and said permanent magnet, means biasing said armature out of said attracted position but incapable of returning the same when in said attracted position, a leakage flux path extending parallel to said electro-magnet and spaced from said armature.

14. A relay including an electro-magnet, a permanent magnet arranged in spaced parallel relationship, and an armature, normally out of contact with, and to one side of both said magnets, and attractable to bridge said electro-magnet and said permanent magnet, means biasing said armature out of said attracted position but incapable of returning the same when in said attracted position.

15. In a polarized relay, in combination, a permanent magnet, an electro-magnet, a pivoted armature normally out of contact with said magnets, elastic means biasing the armature away from said magnets, and effective to retain the armature away from the permanent magnet, when the electro-magnet is de-energized, the armature being drawn against the permanent magnet when the electro-magnet is energized with one polarity.
